METHOD AND APPARATUS FOR MAKING
CENTER SPOT CROWNS

Anders Josef Jonsson, Linkoping, Sweden

Application March 17, 1934, Serial No. 716,050
In Sweden February 25, 1933

19 Claims. (Cl. 113—80)

The present invention relates to a method of and a device for putting so-called facing disks or spots into bottle caps especially in full-automatic machines which make the caps and/or close the bottles. Such machines are provided with tools for introducing into the cap a sealing disk of a material, such as cork, which is elastic to a certain degree.

In recent years machines of this type have been used for closing bottles and receptacles containing beer, mineral water and other drinks. Although cork as a sealing material has proved to be the most suitable, it has several drawbacks. In spite of paraffining or other treatment, cork easily imparts a slight taste to the contents of the container, some drinks having proved to be particularly easily damaged. Furthermore, it is difficult to form cork disks sufficiently free from pores that they do not pass the liquid or carbon dioxide which may be present in the liquid. If liquid penetrates between the cork disk and the cap which is usually of aluminum, the salts which may be present in the liquid may attack the aluminum cap.

To overcome these drawbacks it has been suggested to provide the cork disk with a protective coating or a so-called facing disk of specially prepared paper, tinfoil or the like. The coating is applied to the cork disk by various methods, the most suitable being to apply to one side of the coating a very thin layer of gutta-percha or similar substance, which at relatively low temperature fuses rapidly, thus fixing the coating to the cork disk.

In prior constructions it has been necessary to effect this coating of the cork disk in a process and machine which is completely separate from the cap making and/or the bottle closing process and machine. Devices have been proposed for applying facing disks in combination with the cap making in the same machine, but said devices have proved unsuited for high speed operation.

This invention has for its object to make possible the coating of the sealing disk with the protecting material as part of the cap making and/or the bottle closing operations, so that the making of caps, the introducing of the sealing disk, the procedure of providing the same with a protecting coating and, in certain cases, also the closing of the bottle or receptacle, take place in a continuous process.

Two embodiments of the invention are illustrated in the accompanying drawings.

Figure 1 shows a front view of the machine, the bottom of which is a vertical cross-section along line G—H, of Figure 2.

Figure 2 shows a plan view of the machine table with the parts of the machine disposed thereon; the parts which are above the table and a broken

section plane J—K—L—M, marked in Figure 1, are removed.

Figure 3 shows a section A—B—C—D of Figure 2 and

Figure 4 shows on a larger scale, a section E—F of Figure 2.

Figures 5—12 show, partly diagrammatically, another embodiment of the invention, viz. the mechanism arranged as an additional unit.

Figure 5 is a plan view of the unit, with certain parts omitted for the sake of simplicity.

Figure 6 shows the same in section O—P of Figure 5.

Figures 7 and 8 show side views of one and the same detail the members being in two different positions.

Figure 8a shows a modification of this detail.

Figure 9 illustrates, on a larger scale, a section R—S of Figure 5 and

Figure 10 shows also, on a larger scale, a detail to the left of Figure 5 seen in plan.

Figures 11 and 12 show, on a larger scale, a plan view and a side view of another detail.

The two embodiments of the invention are shown as applied to a machine for making complete caps, i. e. machines, which punch the cap shell blank out of a metal strip, bend the same and put a cork disk into the cap shell thus produced.

Of the known parts of the machine numeral 1 indicates the cap shell punching device for punching out and shaping the cap shell c, 2 indicates a groove in which the cap shell is moved towards the cork inserting tool 3, (in the embodiment shown this takes place by means of compressed air); 4 indicates a tube in which the cork disks a are stacked, 5 is the conveyer which feeds the disks a from tube 4 and is moved to-and-fro by the toothed gear 6 which, by means of the shaft 7, the toothed gear 8 and the rack 9 receives its motion from the shaft 9a, which drives the cap shell punching device. In Figure 1 the conveyer is shown in its one end position and in Figure 2 in its other end position. 14a, 14b and 14c is a safety device which is described in another connection, and which stops the machine, if no sealing disk is fed or if the disk is mutilated. This safety device cooperates in a well known manner with an introducing plunger 21, which forms part of the tool 3, the said plunger being driven by a lever 14e and a push rod 14f, the motion of which is controlled by the said safety device.

The invention relates to a mechanism which, in cooperation with the remaining tools, punches a facing disk b out of the coating material, which is in strip form, attaches the facing disk to the disk and introduces the latter into the cap shell c, whereupon the cap is conveyed in the usual manner to a collecting receptacle or to the closing

member of the capping machine and is applied to the receptacle or bottle.

Numeral 10 indicates a device for feeding the strip from which the facing disks are punched, the said feeding device operating with two rollers. I have shown this strip diagrammatically in Figure 3 by means of a dash-and-dot-line, and in Figure 4 by means of a full line 10a. The feeding device receives its motion from the shaft 7 via a crank 11 disposed on the same, a winch handle 11a disposed on a roller shaft and a connecting-rod 11b connecting both and a step by step device 11c and 11d. 12 is a guide pulley for the strip, which runs in a groove 13 in the machine table.

In the machine table 14, below the coating strip, there is provided a punching device 15 (Figure 4) and a punching die 15a located above the same. The punch, which in Figures 3 and 4 is shown in a pushed up position, receives its up-and-down movement by means of a lever 16 (Figure 2) from a cam 17 on the shaft 7. Among the other parts 15b indicates a bearing bush for the punch. A conveyer 18, which receives its to-and-fro-motion by means of a lever 19 from a cam 20, which is also mounted on the shaft 7, feeds the punched out facing disk to the inserting tool 3. The conveyer 18 runs between two guides 18a, which are secured in the machine table by means of screws 18a'. 18b of Figure 4 indicates a covering plate. In order that the facing disk shall be liberated from the die and come on a suitable level above the same relatively to the conveyer, the punch is provided with a central bore for a pin 18c (Figure 4), which under the action of a spring 18d raises the punched out facing disk to a suitable height above the punch, the said height being determined by a pin-and-groove connection 18e.

40 The punch is stopped in this position owing to the shape of the cam 17, until the conveyer 18 has pushed the facing disk from the pin 18c. In order that the conveyer shall run free of the same, it is provided with a groove 18f on its under side. The introducing plunger 21 of the inserting tool comprises an electric heating element which is fed with current through the wires 22. The upper portion of the introducing plunger, the element 23, is made of a good heat conductor such as copper. The supply of heat is controlled in a known way by means of a rheostat.

The device operates in the following manner.

From the strip 10a, the upper side of which is coated with gutta-percha or the like, the punch 55 15 punches out a facing disk b, which by means of the conveyer 18 is pushed forward in a groove 15c, until it rests on the plunger 21, which is in its lower position. The latter has been connected to the electric current and is hot. Before the 60 plunger 21 starts its upward movement, a cork disk a is introduced by the conveyer 5 from the supply pipe 4 in such a position that it will come above the facing disk b resting on the plunger.

Meanwhile the cap shell punching device has 65 finished the cap shell c and the latter is conveyed up to the cork inserting tool 3 and above the plunger 21 and the facing disk b and cork disk a, which rest on the same. The plunger is then moved upwards and presses the cork disk 70 into the cap at the same time as it presses the facing disk to the cork disk. By heat from the plunger the gutta-percha like coating of the facing disk fuses, and the simultaneous pressing causes the facing disk to stick to the cork disk, so 75 that the cap, when liberated from the tool, to be

conveyed further away to the collecting receptacle or to the closing member, is provided with a cork disk with an applied facing disk of protecting material and ready to be immediately applied to the receptacle or bottle. The cork disk is frictionally held by the cap shell in the usual manner.

5 The facing disk may be placed on the upper side of the cork disk facing the cap shell without the application of heat. It may consist of two or more layers of like or different material 10 united by some adhesive.

So as to prevent the heat from spreading from the plunger 21 to the strip blank for the facing disks which would soften or even melt the coating before the punching out operation and cause the 15 facing disks to stick to one machine member or the other, the path for the strip is kept cooled by blowing air on it through a number of holes 25, which receive compressed air through a conduit from some suitable source of compressed air, for 20 example the fan which delivers compressed air for moving the cap.

In order to insure that the facing disk shall 25 not stick to the cork disk, before the latter is centered in relation to the facing disk, it is necessary that the cork disk be kept well cooled until it is placed above the facing disk and the plunger 21. This cooling may also be effected by means of compressed air. Of course, other members near the introducing punch may also be cooled in 30 the same way.

The hereinbefore described mechanism for inserting facing disks forms an integral part of the cap making machine. When making caps without cork disks or without facing disks one 35 must use a machine without the above mechanism, or if such mechanism is at hand, it must remain inoperative while making the said caps.

The present invention may be used in such a manner that the above mentioned mechanism 40 is made as a separate assembly which may be attached to the machine or removed from the same, depending whether the caps are to be made with or without facing disks. The mechanism may be so constructed that the facing disk is applied 45 either above or below the cork disk in the cap, i. e., either between the cork disk and the cap shell or on the free surface of the disk.

The construction of the unit is such that a 50 great number of cork disks is under treatment at the same time for the application of the facing disks, the disks being moved in one or more lines across a table from a supply pipe or the like. Each is furnished with its facing disk which, by means of a punching tool like the one 55 described above, is cut out of a blank strip. The cork disks are fed stepwise from the supply pipe and pass through a conveyer which pushes the facing disks in their proper turns further past one or more heating plungers, and finally past 60 a number of pressing plungers, which press the facing disks to the cork disks and at the same time cool them, so that they will stick. Thereafter the cork disks are moved into positions to be inserted into the caps, as described before.

65 In Figures 5-12 purely constructive details have been left out or they are only indicated schematically so as to make it easier to understand the figures.

The unit is mounted on a frame plate 30, 70 which is detachably secured to the inner portion 31 of the machine table so as to replace the outer portion 14 (see especially Figure 2) with the associated inserting mechanism for the facing disks.

The fastening device has a foot portion 32 and two screw bolts 33. In practice the same may of course be made in some other way. The supply pipe for the cork disks is cut off a distance 5 above the machine table and the lower portion 4 is associated with an opening 34 in the plate 30, the upper portion 4a being moved a considerable distance to the right above the plate. Between this pipe portion 4a and the opening 34 the cork 10 disks are fed in a line by means of a conveyer, consisting of two bars 35, 36, provided with recesses for the disks. The said bars are movable within certain limits towards and away from one another and moreover synchronously backward 15 and forward in their longitudinal direction. For the first mentioned movement they are guided by two cross pieces 37, 38 (Figures 9, 10) at each end, for the last mentioned movement by two bearings 39, 40, for in one of them runs a rail 41 or a shaft, and in the other a rail 42 or a shaft, each formed from its separate cross piece 37. The bars are provided with stationary rolls 43, 44 on the upper and lower sides, which bars run in guide grooves in the cross pieces. The longitudinal movement of the bars is effected for example by means of a lever 45 (Figure 5), which is connected with the driving mechanism of the machine. On displacing the bars to the left (in Figure 5) they move the cork disks *a* a step, 20 and at the end of the stroke they are moved apart. Upon the displacement of the bars to the right the cork disks remain in their positions. In such a case they are retained by working plungers 46, 47, 48, shown in Figure 6.

35 The latter are secured in a holding member 49, which is mounted in the machine for an upward and downward movement. While the plungers are pressed against the cork disks, preferably by spring pressure, the bars are moved back by the 40 lever 45.

The above mentioned spreading of the bars is effected by wedges 50, 51 (Figures 5, 6, 9, 10), secured on arms 52, 53. Upon the termination of the feeding stroke of the bars, the wedges are 45 simultaneously swung in between the lower rolls 44 when the arm bumps against a shoulder 55 (Figure 5). Both arms are moved simultaneously by means of an adjustable connection 54 consisting of two rods united by means of a screw 50 sleeve 57. When the bars are moved to the right, the wedges and arms follow, but are stopped before the end of the stroke by the arm 53 bumping against a shoulder 56. The bars are freed from the wedges and by the action of springs 80 55 again grasp the cork disks. Another cork disk *a* is then grasped below the pipe 4a and the disk which is furthest to the left, is pushed out on a turning plate 58, mounted above the pipe 4. The purpose of the said plate is to turn the cork 60 disks for a purpose, which will be clear from the following.

The facing disk punch may be constructed and arranged in the same way as in the preceding embodiment, or it may be disposed on the upper 65 side of the blank strip 12x. This punch is not shown in the drawings, but may, for example, be located right above the opening 60 in a cross piece 61. Below this cross piece runs the slide, 70 which pushes each of the facing disks from the stamp to the cork disk. Here the said slide is indicated by 62 and in the drawings it is shown pushed up to a cork disk. It receives its motion from the lever 63 and a cam 64, the shaft 65 of 75 which is journalled at the under side of the plate

30 and is oscillated in the same way as the shaft 1 of Figure 2.

The blank strip 12x is fed forward by means of a feeding device 10 like in the previous embodiment and, therefore it is shown only diagrammatically in this case. The crank 11 is secured on the shaft 65, and by means of the connecting-rod 11b connected with the winch-handle 11a, which drives the feeding mechanism. In this embodiment the arrangement is such 10 that a facing disk is not punched out if no cork disk is fed from the pipe 4a. This control arrangement may be made in different ways. For example, the facing disk punch may be stopped. Another, simpler solution is to stop the feeding mechanism for example by means of the arrangement shown in Figures 5, 7, 8. A control member, preferably in the form of a small lever 10 is by means of a wire 70a running over trundles (not shown) connected with a feeler in the shape 15 of a roll 71, the said feeler resting against the respective cork disk.

If the cork disk is missing, the feeler is pressed down, the member 10 changes its position and raises the pawl 11c, so that the latter will assume the position shown in Figure 8, at which it passes past the underlying notch of the ratchet 11d, when the crank 11 moves to the left, which is repeated until a new cork disk is pushed under the feeler, when the feeding begins again. Figure 8a shows another embodiment, viz. a lever connection 70a' between the roller 71 and the control member 70, 70b indicates a pressure spring which actuates the lever connection. Both the wire and the lever connection 70a may be 30 disposed below the plate 30.

The slide 62 and feeding mechanism 10 preferably cooperate so that during the forward pushing of the facing disk to the cork disk the feeding mechanism stands still, whereas the latter 40 moves the strip forward a step when the slide is moved from the cork disk.

The turning plate 58 (see Figures 11 and 12) is turned through 180° each time, always in the same direction, by means of a rack 14. This 45 rack is carried by the bar 35 and engages a pinion 75 loosely mounted on the spindle of the plate 58. A pawl 76, carried by the pinion 75, engages with a ratchet 77 secured to the spindle of the plate. Accordingly, the plate is turned when the bars 50 are moved away from it, i. e., downwards as viewed in Figures 11 and 12, but remains stationary when the bars are moved toward it, i. e., upwards as viewed in Figures 11 and 12. While the plate is stationary, the outermost cork disk 55 may be pushed out onto the plate, and a flange 78 on the plate serves as a stop for the cork disk.

When the plate is turned the cork disk falls down into the pipe 4, the facing disk *b* being turned down. Therefore, the disk will be fed 60 into the cap by the slide and the plunger 21 (Figures 1, 4, 7) the facing disk *b* still being turned down. The movement of the plate may of course be obtained also by means of some other coupling mechanism than the one hereinbefore 65 described, for example by means of a lever arrangement. In case it is desired that the facing disk be turned upward in the cap, the plate 58 is removed and the cork disk is pushed directly down into the pipe 4 without being turned.

Among the plungers shown in Figure 6 the ones indicated by 46 and 47 are intended for heating, e. g., by electric means as in the former embodiment. The remaining one 48 serves for squeezing fast and for cooling the facing disks.

In the embodiments described the shaping of the cap and the application of the facing disk to the sealing disk take place in the same machine, but the operations may of course also be made in separate machines with the devices described.

Of course constructive changes may be made within the scope of the present invention.

Having now described my invention, what I claim as new and desire to secure by Letters Patent is:

1. In a bottle cap machine, a frame plate, a supply pipe for sealing disks above the plate, a storing tube for the disks below the plate, a first 15 conveyer for moving sealing disks from the pipe to the tube, a feeding device laterally of the conveyer for feeding a blank strip for facing disks, a punching instrument past which said strip is fed, another conveyer on the plate for transferring a 20 facing disk from the punching instrument to each sealing disk fed from the supply pipe, and a plurality of pressing plungers above the plate along the path of the sealing disks for securing the facing disk to the respective sealing disk.

25 2. A device according to claim 1, in which said first conveyer for the sealing disks consists of two bars with recesses for the sealing disks, the said recesses facing each other, means for moving said bars to and fro, wedges cooperating with bars 30 of said first conveyer, means for actuating said wedges when the sealing disks have been fed one step to move the bars apart, means for operating the wedges to follow the conveyer until the latter has reached the end position, and means operative thereupon for moving the wedges out of the engagement with said bars.

3. A device as claimed in claim 1, characterized by the fact that at least one of the plungers comprises heating means, the rest of the plungers 40 being pressing and cooling plungers.

4. A device according to claim 1, characterized by a turning plate above the storing tube for turning the sealing disks one after the other so that the facing disk will be turned down in the 45 storing tube, means for turning said plate half a turn between each sealing disk fed thereto, said last mentioned means including mechanism actuated by the first conveyer for the sealing disks.

5. A device according to claim 1, characterized by a feeler in the path of the sealing disks, means 50 operative when no disk is fed for reversing said feeler and stopping supplying of facing disks until another sealing disk has been fed.

6. A device according to claim 1, characterized 55 by a feeler in the path of the sealing disks, a motion transmitting device, said feeding device comprising a step-by-step hook with which said motion transmitting device connects said feeler, for the stepwise driving of the same, and means 60 for moving said hook out of engagement so that the feeler changes its position when a sealing disk is lacking.

7. In the herein-described method of making complete bottle caps of the character described, 65 the steps which consist in supplying a plurality of cap shells and a plurality of sealing disks, forming a plurality of facing disks each having adhesive material on one surface, advancing a sealing disk and a facing disk edgewise into centered superposed relation, and pressing said superposed disks simultaneously into a cap shell.

8. The steps set forth in claim 7, in which the

facing disks are punched out successively from a continuous blank of material.

9. The steps set forth in claim 7, in which said pressure is carried out under application of heat.

10. In the method set forth in claim 7, the additional step of bonding the superposed sealing and facing disks together before they are pressed into the cap shell.

11. In a machine for making bottle caps of the character described, a support for a cap shell, 10 means for feeding a sealing disk into centered superposed relation to the cap shell, an instrument for punching facing disks from a blank strip, said punching instrument being laterally disposed with respect to said cap shell support, 15 a conveyer for advancing a facing disk edgewise from said punching instrument into centered superposed relation to the sealing disk, and means for pressing said superposed sealing and facing disks simultaneously into the cap shell. 20

12. In a machine for making bottle caps of the character described, a support for a cap shell, means for feeding a sealing disk into centered superposed relation to the cap shell, a plunger 25 for pressing said sealing disk into the cap shell, an instrument for punching facing disks from a blank strip, said punching instrument being disposed laterally alongside of said plunger, and a conveyer for advancing a facing disk edgewise from said punching instrument into centered 30 superposed relation on said plunger, whereby said plunger may thereupon press said sealing and facing disks in superposed relation simultaneously into the cap shell.

13. In a machine as set forth in claim 12, an 35 electric heating element associated with said plunger so that said pressure may be accomplished with the application of heat to said disks.

14. In a machine of the character described, the combination with the elements set forth in 40 claim 12 of a yieldable means carried by the punching instrument for raising the punched-out facing disk above the level of the working surface of the punching instrument.

15. In a machine of the character described, 45 the elements set forth in claim 12, said conveyer comprising a slide, guide rails on opposite sides of the punching instrument and between which rails said slide moves, a lever articulated to the slide for reciprocating the latter, a driving shaft, 50 and a cam driven by said shaft for controlling the movements of said lever.

16. In a machine as set forth in claim 12, an electric heating element associated with said plunger so that said pressure may be accomplished with the application of heat to said disks, 55 and means for applying cooling air to said disks to prevent overheating thereof.

17. In the herein-described method of making complete bottle caps of the character described, 60 the steps which consist in advancing a sealing disk and a facing disk edgewise into centered superposed relation, the facing disk having adhesive material on one surface, and pressing said superposed disks simultaneously into a cap shell. 65

18. The steps set forth in claim 17, in which said pressure is carried out under application of heat.

19. In the method set forth in claim 17, the additional step of bonding the superposed sealing and facing disks together before they are pressed into the cap shell. 70

ANDERS JOSEF JONSSON.
